CLAIM

The ornamental design for a water outlet nozzle, as shown and described.

DESCRIPTION

FIG. 1 is a front and left side perspective view of a water outlet nozzle, showing my new design.

FIG. 2 is a front and right side perspective view thereof.

FIG. 3 is a rear and left side perspective view thereof.

FIG. 4 is a front view thereof.

FIG. 5 is a rear view thereof.

FIG. 6 is a left side view thereof.

FIG. 7 is a right side view thereof.

FIG. 8 is a top view thereof; and,

FIG. 9 is a bottom view thereof.

The broken lines showing the water outlet nozzle are included to illustrate portions of the article and do not form part of the claimed design.
